SHUTTLE FOR AUTOMATIC LOOMS

William A. Tebo, Anthony, R. I., assignor to
 Draper Corporation, Hopedale, Mass., a corporation of Maine

Application May 1, 1936, Serial No. 77,394

3 Claims. (Cl. 139—223)

The present invention pertains to automatically threading loom shuttles for automatic looms, and has more particular reference to the threading devices of such shuttles.

5 Shuttles of the type to which the invention pertains are comprised of a shuttle body having a threading block which has a longitudinal thread passage and a horn which projects from the front wall of the threading block outwardly and rearwardly above the thread passage. The running filling becomes threaded into the thread passage below the horn during the first pick after transfer, and is intended to be guided by the horn forwardly and downwardly into the side delivery eye during the second pick after transfer. In view of the possibility of the filling becoming unthreaded from beneath the horn instead of threading into the side delivery eye, it is desirable that the shuttle be provided with thread trapping means to hold the filling against unthreading, and to thereby insure the threading of the filling into the side delivery eye.

It is an object of the present invention to provide a shuttle of the type mentioned, which shuttle shall have a novel and improved form of thread trapping means for holding the filling against unthreading as aforesaid.

The aforementioned and other objects of the invention are accomplished by the construction illustrated on the accompanying drawing, of which:

Fig. 1 is a plan view of the thread delivery and of a shuttle comprising the preferred embodiment of the invention;

Fig. 2 is a view in cross-section taken approximately on line 2—2 of Fig. 1, but to a larger scale; and

Fig. 3 is a view in cross-section taken approximately on line 3—3 of Fig. 2.

40 The shuttle shown on the drawing is comprised of a shuttle body 1 having a longitudinally extending cavity 2 for reception of a filling carrier, such as bobbin 3, and certain threading devices to be hereinafter described. The shuttle, being for use in an automatic loom of the bobbin-changing type, is provided with suitable usual means (not shown) for releasably holding the filling carrier in the cavity whereby the filling carrier may be automatically replaced by a new one whenever the filling supply becomes substantially exhausted.

45 The threading devices include a side delivery eye formed in the shuttle body at 4, and a threading block fixed in a recess 5 in the shuttle body. The threading block has a longitudinally ex-

tending thread passage in alignment with the cavity 2, the thread passage being defined by the floor 6 and front and rear walls 7 and 8, respectively, of the threading block. The threading block has a horn 9 which projects from the front wall 7 outwardly and rearwardly above the thread passage. The rearward end of the horn is free and is preferably turned downwardly, as at 10, into a groove 11 which is formed in the shuttle body. The groove 11 extends from the recess 5 longitudinally outwardly, the groove being approximately in alignment with the recess and thread passage and communicating directly therewith.

5 It may be here noted that expressions denoting direction, as herein employed, are applicable to the shuttle when the latter is considered to be positioned in a loom and boxed at the side of the loom toward which the tip 12 points. Thus, "forwardly" is in a direction from the top of the sheet of drawing toward the bottom thereof on Fig. 1, and "outwardly" is in a direction from the cavity 2 toward the tip 12 of the shuttle.

6 The transfer of a filling carrier into the cavity 2 occurs at a time when the shuttle is boxed as described. The filling end 7 then extends from the filling carrier in the shuttle outwardly and upwardly, over the threading block, to the usual fixed holder (not shown). Thereafter, the shuttle is moved bodily rearwardly and then picked 30 in a direction toward the left, Fig. 1. As the shuttle is picked, the filling unwinds from the filling carrier and in unwinding swirls or balloons about in a manner to become threaded down into the thread passage and beneath the horn 9. The filling threads down into the thread passage and groove 11, beneath the horn 9, very early in the first pick after transfer, and continues to run in such position throughout the remainder of the pick. When the shuttle is picked 40 in the opposite direction, the filling is intended to be guided by the horn through a suitable opening 13 into the side delivery eye 4. The present invention provides a wire thread trapping member for guarding the end of the horn 9 and thus 45 preventing the filling from unthreading from beneath the horn.

7 The thread trapping member shown on the drawing is comprised of a single piece of wire having legs 14 and 15, and a connecting bar 16. 50 The leg 14 is formed at the inner end of the wire and is fixed at 17 in the rear wall of the recess 5 as by being driven into the wood of the shuttle body. The point 17 at which the member is fixed to the shuttle body is inwardly of the 55

shuttle from the horn and materially higher than the bottom of the down-turned end 10. From the point 17, the leg 14 is inclined forwardly and downwardly to a point forwardly of 5 the end 10 of the horn, for a purpose to be described.

The connecting bar 16 of the thread trapping member extends from the front end of the leg 14 longitudinally outwardly beneath the horn 9. 10 It will be noted that the bar is positioned in the thread passage and groove approximately centrally thereof, it being above the bottom of the groove and also above and forwardly of the bottom of the down-turned end 10. The connecting 15 bar as shown on the drawing inclines slightly downwardly from its inner to its outer end. The outer leg 16 of the thread trapping member is fixed in the groove 11 as by being driven into the rear wall of the groove above the bottom 20 thereof.

The purpose of the inclination of the leg 14 of the trapping member is to facilitate threading of the filling down into the groove 11. For this same purpose, the rear face of the down-turned 25 end 10 of the horn may be inclined downwardly and forwardly as shown on Fig. 3. Thus, when the shuttle is started on the first pick after transfer, the filling will swirl rearwardly and downwardly about the rearward free end of the 30 horn and will strike against the inclined leg 14. The filling will then be drawn or pulled forwardly and will be deflected downwardly and forwardly to pass beneath the down-turned end 10 of the horn. As the shuttle continues its flight the filling 35 will assume a running position in the thread passage and groove beneath the thread trapping member. It will be obvious that the thread trapping member will positively prevent the filling in the thread passage and groove beneath the 40 member from unthreading about the free end of the horn. Thus, the entry of the filling into the side delivery eye during the second pick after transfer is insured.

Having fully disclosed the preferred embodiment of my invention, I claim:

1. An automatically threading loom shuttle comprising a shuttle body having a bobbin-receiving cavity therein, a threading block fixed in a recess in said shuttle body, said threading block 50 having a longitudinal thread passage and a horn which projects outwardly and rearwardly above said thread passage, the rearward end of said horn being free and being turned downwardly into a longitudinally extending groove provided 55 therefor in said shuttle body, and a guard wire

having its inner end fixed in the rear wall of said recess and its outer end fixed in said groove at a point outwardly from said horn, said guard wire between its ends extending longitudinally of said thread passage and groove beneath said horn, the said longitudinally extending part of 5 said guard wire being positioned forwardly of and above the down-turned end of said horn.

2. An automatically threading loom shuttle comprising a shuttle body having a bobbin-receiving cavity therein, a threading block fixed in a recess in said shuttle body, said threading block having a longitudinal thread passage and a horn which projects outwardly and rearwardly above said thread passage, the rearward end of 10 said horn being free and being turned downwardly into a longitudinally extending groove provided therefor in said shuttle body, and a wire thread trapping member having outer and inner legs and a bar connecting the same, said 15 inner leg being fixed in the rear wall of said recess and being inclined downwardly and forwardly, said outer leg being fixed in said groove at a point outwardly from said horn, said connecting 20 bar extending from said inner leg longitudinally outwardly in said thread passage and groove beneath said horn, said bar being positioned forwardly of and above the down-turned end of said horn.

3. An automatically threading loom shuttle comprising a shuttle body having a bobbin-receiving cavity therein, a threading block fixed in a recess in said shuttle body, said threading block having a longitudinal thread passage and a horn which projects outwardly and rearwardly above 30 said thread passage, the rearward end of said horn being free and being turned downwardly into a longitudinally extending groove provided therefor in said shuttle body, and a wire thread trapping member having outer and inner legs 35 and a bar connecting the same, said inner leg being fixed in the rear wall of said recess and being inclined downwardly and forwardly, said outer leg being fixed in the rear wall of said groove above the bottom of the latter, said connecting 40 bar extending from said inner leg outwardly beneath said horn to said outer leg, said connecting bar being positioned in said thread passage and groove forwardly of and above the down-turned end of said horn, whereby the running filling is guided into said thread passage and 45 groove beneath said thread trapping member and is thereafter prevented from unthreading rearwardly about the free end of said horn.
